165,469

WINGED DOLL

Leah Katz, New Orleans, La.

Application February 13, 1951, Serial No. 14,197

Term of patent 14 years

(Cl. D34—4)

To all whom it may concern:

Be it known that I, Leah Katz, a citizen of the United States, residing at New Orleans, parish of Orleans, and State of Louisiana, have invented a new, original, and ornamental Design for a Winged Doll, of which the following is a specification, reference being had to the accompanying drawings, forming a part thereof, wherein:

Figure 1 is a front elevational view of a winged doll, showing my new design.

Figure 2 is a rear elevational view.

Figure 3 is a side elevational view.

Figure 4 is a top plan view.

I claim:

The ornamental design for a winged doll, as shown.

LEAH KATZ.
